LAST

James B. Waterfield, Attleboro, Mass.

Application August 29, 1933, Serial No. 687,289

10 Claims. (Cl. 12—139)

This invention relates to a last such as is used in the shoe industry; and has for one of its objects the provision of a last which will not split or splinter during its use, more particularly when inserted in a heeling and leveling machine.

Another object of the invention is the provision of a construction by which lasts of different sizes may be made substantially of the same height to avoid the necessity of adjusting the machine in which they are used.

Another object of the invention is the provision of a reinforcing top for the last, which may be effectively secured in position in a less expensive and simpler manner than reinforcements which have heretofore been applied to the tops of shoe lasts.

Another object of the invention is the provision of a reinforcement for the top of the shoe last which may be securely held in place and one which will not work loose and come off due to shocks or jars in the uses to which the last is subjected while in the process of work.

Another object of the invention is the provision of a top reinforcement for the shoe last which may be provided in different colors and of such a character that these colors will not be worn off or need replenishing during the life of the last.

Another object of the invention is the provision of reinforcements which may be transferred from one last and positioned on another last, should the first last be no longer used.

With these and other objects in view, the invention consists of certain novel features of construction, as will be more fully described, and particularly pointed out in the appended claims.

In the accompanying drawing:

Fig. 1 is a perspective view of a hinge last provided with my improved metal top.

Fig. 2 is a central sectional view thru the top portion of the last, a part of which is shown in this figure.

Fig. 3 is a section on the line 3—3 of Fig. 2.

Fig. 4 is a sectional view of the top member.

Fig. 5 is a sectional view of the bottom member.

Fig. 6 is a sectional view of the top member on line 6—6 of Fig. 4.

Fig. 7 is a side elevation illustrating the member of the metal top as being provided with different colors.

In the building of shoes, lasts are used about which the same are formed. These lasts are formed of wood as a most desirable material and it is found in the use of this wood that when the

last with the shoe thereof, is positioned in a heeling and leveling machine and subjected to considerable pressure during the application of the heels to the shoes, that the top of the last frequently cracks or splinters and after several operations becomes unfit for further use.

This splintering creates a liability of the splinters entering the operator's hands and also damaging the lining of the shoe. Reinforcements have been applied to the lasts in the form of metal and leather.

The metal reinforcements have an objection of being unyielding and also thru the shocks or jars to which they are subjected, the fasteners for these metal tops are loosened to such an extent that the metal will come off the last, while in the use of leather tops several additional parts are necessary for strengthening the last in its use and in order to overcome these difficulties I have provided a metal top in two pieces, one of which is secured to the last and

the other of which locks the securing means for this first part in position, while by reason of the two metal parts providing metal to metal surfaces I am enabled to secure these parts together so that they cannot be dislodged one from the other

and in order that some of the shocks which have been received by the metal may be absorbed and not transmitted to the wooden last, I have provided a cushioning means between these two metal parts for this purpose. Further in order

that this top may be provided with a distinguishing color I have coated it with a metallic material which may be dyed to provide a fixed and indelible color on the top by which lasts of a certain size may be distinguished as they are being

worked in the factory, and the following is a more detailed description of the present embodiment of this invention illustrating the preferred means by which these advantageous results may be accomplished:

With reference to the drawing, 10 designates the toe part and 11 the heel part of my hinged last, which parts are hinged to swing one relative to the other by a pivot pin entering the opening

12, as is usual in lasts of this character. The bottom of the heel 13 is usually provided with a metal plate and above this heel portion I provide the metal top designated generally 14, as a reinforcement for this portion of the last, which is tapered to a smaller mass and is subjected to the pressure of the heeling and leveling machine, in nailing the heel to the shoe.

The heel portion of the last 11 is provided with a flat surface 15 which is in a plane generally parallel to the plane of the lower surface of

the heel 13. Upon this flat surface 15 a base member or plate 16 is provided, the under surface of which is of a size and shape to cover the surface 15 and this member is secured to the 5 last by a screw 17 at the heel end and the screws 18 at the forward end, which extend thru suitable openings 19 and 20 in the body plate and enter the wooden heel portion 11 of the last, as illustrated in Fig. 2.

10 The base member 16 is provided with centering openings 21 and a top member 22 is provided with projections 23 which enter the openings 21 to maintain these plates in their desired assembled relation. The body plate 16 on its 15 edge surfaces is tapered as at 24 to conform generally to the narrowing shape of the last as it is shaped to conform to the shape of the foot, while the edge 25 is also inclosed to conform to the cut-away portion 26 allowing for the swinging of the 20 two parts 10 and 11 of the last with reference to each other. Thus the upper surface 27 of the base member is smaller than the base surface and this surface 27 is of the same size or substantially the same as the bottom surface 28 of 25 the top member, while the edges 29 and 30 of the top plate continue the same inclined direction as that of the base member and provide a smaller top than bottom for this metal reinforcement and conform to the general shape of the last. 30 These members are locked together by a rivet pin 36 extending thru an opening 34 in the base member and an opening 35 in the projections 23 which register with this opening to receive the rivet pin 36 which is headed over at its ends to 35 secure the same in position and the members in assembled relation. By the provision of one member being locked to the other and covering the screws by which the base member or plate is secured to the last, these screws cannot be removed by jars which often work such fastenings loose and thus the metal top is securely held in 40 position against accidental removal.

These members are provided with openings 31 and 32 which register one with the other and 45 also register with a bore 33 in the last for the reception of a rod in the heelng machine for correctly positioning the last in this machine.

The upper surface of the top plate 37 is arcuate or concaved so as to also assist in centering 50 the last on the curved surface of the heelng machine and is found to be of great advantage in the manipulation of the last of this character.

In order that shocks may be absorbed to some extent I have provided a cushioning element 38 positioned between the members 16 and 22, 55 which may be of rubber, pressed fiber, or any other suitable material to assist in absorbing the shocks.

There is a slight play of the rivets 36 in their 60 openings 34 and 35 which allows for compression of the cushioning member 38.

It is found desirable in the use of lasts in factories to provide a designating color for the different sizes. For instance, width A may be the 65 natural color or white; width B-green; width C-blue and width D-red; width E-orange or any like scheme, and to accomplish this it is usual to dob some sort of paint of a color on the last in order that the operator may know the size 70 which is being worked.

The metal which I prefer to use for this improved top will be of a light weight and I have found that "Nicral", an alloy containing a high percentage of aluminum and some chromium and nickel, is suitable for this purpose, and in order

that a color may be provided on this metal, I have coated the same with "Alumilite" or a substance largely an oxide of aluminum which is more or less hydrated and contains more or less sulphate. This "Alumilite" is formed in a solution containing sulphuric acid and water together with various additional agents. The properties of the coating are largely determined by the acid concentration and the temperature of the Alumilite and the additional agents. The 10 process consists of electro chemical oxidation and involves a colloidal phenomena. The coating is sufficiently porous to absorb colors and may be dyed with both organic and inorganic dyes and thus various colors may be had upon its surface 15 and where fast dyes are used these colors will not fade. The coating also has the property of being very hard and may be polished without removing the color and thus an indelible color is provided on the last, which is of particular and 20 special advantage in its connection with lasts.

I have shown in Fig. 7 the color orange at 40, while I have shown the base as dyed the color black at 41 thus providing a contrast for the determining of half sizes, or other various combinations as may be produced.

The foregoing description is directed solely towards the construction illustrated, but I desire it to be understood that I reserve the privilege of resorting to all the mechanical changes to 30 which the device is susceptible, the invention being defined and limited only by the terms of the appended claims.

I claim:

1. In a last, a metal top comprising two members, means extending from the upper surface of one member through said member to the last, and means for securing the other member on the upper surface of the first member, said second member covering the securing means for the first 40 member so as to lock the covered securing means in place.

2. In a last, a metal top comprising two metal members, screws for securing one member to the last, and means for securing the other member to the first member, said second member covering said screws so as to lock the screws in place.

3. In a last, a metal top comprising two members, means for securing one member to the last, means for securing the other member to the first member, said second member covering the securing means for the first member so as to lock the covered securing means in place, and a resilient means between said members.

4. In a last, a metal top comprising two members, means for securing one member to the last, and rivets extending thru portions of said members for securing them together, said second member covering the securing means for the first member so as to lock the covered securing means 60 in place.

5. In a last, a metal top comprising two members, screws for securing one member to the last, and rivets extending thru portions of said members for securing them together, said second member covering said screws so as to lock the screws in place.

6. In a last, a metal top comprising two members, means for securing one member to the last, means for securing the other member to the first member, said second member covering the securing means for the first member so as to lock the covered securing means in place, and centering means to positively position the members with relation to each other.

7. In a last, a metal top comprising two members, means for securing one member to the last, means for securing the other member to the first member, said second member covering the securing means for the first member so as to lock the covered securing means in place, and registering openings thru said members for the reception of the rod of the heeling machine.

8. In a last, a metal top comprising two members, means for securing one member to the last, means for securing the other member to the first member, said second member covering the securing means for the first member so as to lock the covered securing means in place, and centering means to positively position the members with relation to each other, said centering means comprising a projection on one member and a recess to receive it in the other member.

9. In a last, a metal top comprising two members, means for securing one member to the last,

means for securing the other member to the first member, said second member covering the securing means for the first member so as to lock the covered securing means in place, centering means to positively position the members with relation to each other, said centering means comprising a projection on one member and the other member having a recess to receive it, and rivets extending thru said centering means to lock the members together.

10. In a last, a body portion formed of wood and having a flat surface above the heel and in a plane generally parallel to the lower surface of the heel, a metal top resting on said flat surface consisting of two parts, one part in contiguous relation with said flat surface, means for securing said part to the flat surface and the other part covering said securing means, and means for attaching the said parts together.
